US00D906284S

(12) **United States Design Patent** (10) Patent No.: **US D906,284 S**
(45) Date of Patent: **** Dec. 29, 2020**

(54) **PLAYBACK DEVICE**

(71) Applicant: **Sonos, Inc.**, Santa Barbara, CA (US)

(72) Inventors: **Mieko Kusano**, Santa Barbara, CA (US); **Wai-Loong Lim**, San Francisco, CA (US); **Hilmar Lehnert**, Framingham, MA (US); **Ong Kok Aun**, Bayan Lepas (MY); **Koh Eng Giap**, Sungai Dua (MY)

(73) Assignee: **Sonos, Inc.**, Santa Barbara, CA (US)

(**) Term: **15 Years**

(21) Appl. No.: **29/676,430**

(22) Filed: **Jan. 10, 2019**

CLAIM

The ornamental design for a playback device, as shown and described.

DESCRIPTION

FIG. 1 is an isometric front view of a playback device. FIG. 2 is a front view of the playback device of FIG. 1. FIG. 3 is a rear view of the playback device of FIG. 1. FIG. 4 is a top view of the playback device of FIG. 1. FIG. 5 is a bottom view of the playback device of FIG. 1. FIG. 6 is an end view of the playback device of FIG. 1; and, FIG. 7 is another end view of the playback device of FIG. 1.

The features shown in broken lines do not form part of the claimed design.

1 Claim, 4 Drawing Sheets

Related U.S. Application Data

a continuation of application No. 29/425,045, filed on Jun. 19, 2012, now Pat. No. Des. 721,352.
